ATTORNEY

UNITED STATES PATENT OFFICE.

ROBERT GOLDE, OF BROOKLYN, ASSIGNOR TO THE ROYAL METAL
MANUFACTURING CO., OF NEW YORK, N. Y.

DESIGN FOR A PICTURE-FRAME.

SPECIFICATION forming part of Design No. 23,249, dated May 8, 1891.

Application filed March 31, 1894. Serial No. 505,953. Term of patent 3½ years.

To all whom it may concern:

Be it known that I, ROBERT GOLDE, a subject of the Emperor of Germany, residing at Brooklyn, in the county of Kings and State of New York, have invented and produced a new and original Design for Picture-Frames and the Like, of which the following is a specification, reference being had to the accompanying drawing, forming part thereof.

10 The drawing shows a plan view of my design adapted for picture frames, plaques and the like.

My design consists in the elliptical border 1, defined by the inner and outer beads 2, 3, 15 circumscribing the elliptical opening 4. Within the heading, and at regular intervals apart are scroll-like foliated figures 5, parts of which

merge into the inner and outer beads, and between each of the figures 5, are smaller foliated scroll-like figures 6, 7, 8, and dispersed about said figures and between them and the beads are small single flowers 9. At the bottom of the border, equidistant from the axis of the ellipse, are scroll-like projections 10, having the flower 11, and leaf 12.

Having described my design, I claim--

The design for a picture frame and the like, substantially as herein shown and described.

Signed at the city, county, and State of New York this 26th day of March, 1894.

ROBERT GOLDE.
